(57) **CLAIM**

The ornamental design for a citrus juicer as shown and described.

DESCRIPTION

FIG. 1 is a top perspective view of a citrus juicer;
FIG. 2 is a front elevational view thereof;
FIG. 3 is a rear elevational view thereof;
FIG. 4 is a top plan view thereof;
FIG. 5 is a bottom plan view thereof;
FIG. 6 is left-side elevational view thereof; and,
FIG. 7 is a right-side elevational view thereof.
The broken lines show portions of the citrus juicer that form no part of the claimed design.
